US0D1061849S

(12) **United States Design Patent** (10) Patent No.: **US D1,061,849 S**
(45) Date of Patent: ** Feb. 11, 2025

(54) **VENTILATING FAN**

(71) Applicant: **Shenzhen Pepnice Technology Co., Ltd.**, Shenzhen (CN)

(72) Inventors: **Jianwei Hu**, Guangdong (CN); **Wei Liu**, Guangdong (CN); **Zhuangneng Meng**, Guangdong (CN); **Haiqin Li**, Guangdong (CN)

(**) Term: **15 Years**

(21) Appl. No.: **35/520,749**

(22) Filed: **Apr. 13, 2024**

(80) **Hague Agreement Data**

Int. Filing Date: **Apr. 13, 2024**

Int. Reg. No.: **DM/236632**

Int. Reg. Date: **Apr. 13, 2024**

Int. Reg. Pub. Date: **May 3, 2024**

(51) **LOC (15) Cl.** 23-04

(52) **U.S. Cl.**

USPC **D23/370**; D23/383

(58) **Field of Classification Search**

USPC D23/370-373, 375, 382-383, 411

CPC F04D 19/002; F04D 29/4253
